VAPOR GENERATOR

Martin Frisch, New York, N. Y., assignor to Foster Wheeler Corporation, New York, N. Y., a corporation of New York

Application November 13, 1945, Serial No. 628,115

20 Claims. (Cl. 122—323)

1

This invention relates to vapor generators.

The present invention provides a vapor generator in which the parts thereof are so constructed and arranged that a minimum amount of heating surface is required for a given vapor generating capacity. This invention also provides a vapor generator in which the combustion air is delivered thereto at higher than normal density and pressure. The present invention further provides a vapor generator in which the combustion air is delivered thereto at higher than normal density and pressure by a compressor which compressor is driven by a gas turbine actuated by combustion products from the generator.

The features and advantages which characterize the invention will be apparent from the following description when considered in connection with the accompanying drawings forming a part thereof and in which:

Fig. 1 is a transverse sectional view of the vapor generator of the present invention taken on the line 1—1 of Fig. 2;

Fig. 2 is a sectional view taken on the line 2—2 of Fig. 1;

Fig. 3 is a view similar to Fig. 2 but is taken on the line 3—3 of Fig. 1;

Fig. 4 is a longitudinal sectional view taken on the line 4—4 of Fig. 2; and

Fig. 5 is a diagrammatic view disclosing the arrangement of the various parts of the apparatus of the present invention.

Like characters of reference refer to the same parts throughout the views.

Referring to the drawings, the vapor generator of the present invention comprises a setting 10 having a cylindrically-shaped outer refractory wall 11 with a metal casing 12 around the outer periphery thereof. The casing 12 is composed of a plurality of sections, as shown, which sections are secured to vertically extending angle bars 14. The angle bars 14 and the casing 12 are supported at the bottom thereof on an annular girder 15. Setting 10 has a dome-shaped metal top 16 with a flange 17 adapted to abut a flange 18 at the top of the casing, the flanges being secured together by bolts 19.

A substantially vertical drum 20 is disposed centrally of the space formed by the cylindrically-shaped wall 11 which drum comprises an upper chamber 21 and a lower chamber 22 spaced from one another and in communication through a downcomer section 23 of a lesser diameter than the chambers 21 and 22. The chamber 21 has a manhole opening 21' at the top thereof which is closed by a cover 21" while the chamber 22 has

a manhole opening 22' at the bottom thereof closed by a cover 22". The downcomer section 23 extends along the longitudinal axis of the drum and is insulated by a covering of refractory 24. A plurality of concentric circular rows of vapor generating tubes 25 are disposed between the lower end of the chamber 21 and the upper end of the chamber 22, the tubes being in communication at the opposite ends thereof with said chambers respectively. As shown, tubes 25 are slightly bowed so that they may be withdrawn through the opening 21'. Tubes 25 are inclosed in a passage 26 by a cylindrical outer wall 27 which has a flange 28 at the top thereof secured to an annular angle bar 29. The angle bar 29 is, in turn, secured to the drum 20 adjacent the chamber 21. The passage 26 is divided into two passes 30 and 31 by diametrically opposed substantially vertical baffles 32 and 33 positioned in passage 26. The baffles 32 and 33 extend to a point short of the top of the passage 26 to provide an opening so that passes 30 and 31 will be in communication with one another. The setting has a substantially circular floor above the chamber 22 comprising a metallic plate 34 having a covering of refractory 35 thereover and a circular roof comprising an annular metallic plate 36. The metallic plate 36 is spaced from the dome-shaped top 16 to form a chamber 16' into which air under pressure is introduced through an air inlet connection 34, as will hereinafter be fully described. Plate 36 is secured at the inner periphery thereof to the angle bar 29 and at the outer periphery thereof to a circular header 37 around the setting at the top of the wall 11. A plurality of water wall tubes 38 project from the header 37 across the roof of the setting along the cylindrical wall 27 of the passage 26 thence across the refractory floor 35 to a circular header 39 around the setting below the refractory wall 11. The tubes 38 are closely spaced along the wall 27 but are spaced apart a greater distance at the point of connection thereof to the headers 37 and 39. Refractory 40 is placed between the roof plate 36 and the portion of the tubes 38 projecting across the roof of the setting. Header 37 is in communication with the chamber 21 of the drum 20 through a plurality of tubes 41 while the header 39 is in communication with the chamber 22 of said drum through tubes 42.

The space between the outer wall 27 of the passage 26 and the outer peripheral wall 11 of the setting is divided into a separately fired vapor generating section 43 and a separately fired superheater section 44 by diametrically opposed

water wall screens 45 and 46 which extend radially adjacent the baffles 32 and 33 across the space between the walls 27 and 11. The screen 46 comprises a row of spaced substantially vertical tubes 47 connected to a lower header 48 and an upper header 49 while the screen 45 comprises a row of spaced tubes 50 which extend substantially vertically between a lower header 51 and an upper header 52. The upper headers are in communication with the upper chamber 21 of the drum 20 while the lower headers of the sections are in communication with the lower chamber 22 of said drum. A semi-circular vapor generating furnace chamber 52 is thereby formed to the left of the screens 45 and 46 while a semi-circular shaped superheater furnace chamber is formed to the right of the screens 45 and 46 as shown in Figs. 1 and 2. Vapor generating furnace chamber 52 has a plurality of tangent water wall tubes 54 along the outer periphery of said chamber adjacent the wall 11, the tubes 54 being connected at their upper ends to the circular header 37 and at the lower ends to the circular header 39. A substantially vertical superheater inlet header 55 extends along the outer periphery of the casing 12 adjacent the screen 45 while a superheater outlet header 56 extends vertically along the outer side of said casing adjacent the screen 46. A row of substantially horizontal superheater tubes 57 are in communication at one end thereof with the header 55 and at the opposite end with the header 56. Each of the tubes 57 has a portion 58 which projects inwardly from the header 55 to a point adjacent the water wall tubes 38 and another portion 59 which projects outwardly from the tubes 38 to the inner periphery of the refractory wall 11. From the portion 59, the tubes 57 are bent to form a radiant section 60 along the inner periphery of the refractory wall 11 to a point adjacent the header 56 at which point the tubes project inwardly to a point adjacent the tubes 38 to form a section 61 and are thereafter bent to form a section 62 which projects outwardly from a point adjacent the tubes 38 to the header 56. In this manner, convection superheating sections comprising the portions 58 and 59 and sections 61 and 62 are formed while a radiant superheating section comprising the portion 60 of the tubes 57 is formed along the wall 11. The section 60 of the tubes 57 are tangent while the portions of the tubes 57 forming the convection superheating sections are spaced apart sufficiently to permit the flow of gases therebetween.

Superheater tubes 57 are divided into a plurality of passes so that vapor to be superheated will flow in series through the various passes from the upper part of the furnace chamber where the saturated vapor enters the header 55 through the connection 82 to the superheated steam outlet 56 at the lowermost part of the header 56. As shown, the inlet header 55 is divided into a plurality of separate chambers 92 by partitions 93 while the outlet header 56 is divided into a plurality of compartments 94 by partitions 95. The chambers 92 and compartments 94 are so disposed in the headers 55 and 56, respectively, that a plurality of superheater tubes 57 comprising a pass 96 connect the uppermost chamber and compartment while the next lower group of tubes 57 comprising a pass 97 connect the uppermost compartment 94 of the header 55 with the chamber 92 which is the next lower chamber to the uppermost chamber. The succeeding lower groups of tubes 57 serially connect a chamber 92 with a lower compartment 94 and the lower compart-

ment 94 with the next succeeding lower chamber 92 for as many passes as may be required to give the vapor being superheated the necessary velocity through the tubes 57 to produce the inside heat transfer rate required to prevent overheating of the tubes.

The superheater furnace chamber 53 is separately downwardly fired by a burner 63 while the vapor generating furnace chamber is separately fired in a similar manner by a burner 64. The wall 27 extends to a point short of the floor 35 at the left of sections 45 and 46 to thereby form a furnace gas outlet opening 65 from the vapor generating furnace chamber 52. The refractory floor 35 extends inwardly in the vapor generating section to the refractory insulation 24 while in the vapor superheating section the refractory floor extends inwardly to the wall 27 to form a gas outlet opening 66 from the passage 31. Refractory 67 is positioned along the portion of the drum 21 bordering the passage 66. The passage 66, as shown, is in communication with a passage gas outlet 68 which is connected to a gas turbine, as hereinafter set forth.

25 A vapor and liquid separator 69 is disposed in the chamber 21 of the drum 20. Separator 69 comprises a cylindrically shaped shell 70 of a lesser diameter than the chamber 21 said shell forming a centrifugal chamber 71. The cylindrically shaped shell 70 has a frusto-conical shaped bottom 72 which abuts the upper end of the downcomer 23 and is adapted to discharge thereinto through an outlet 73. The shell 70 at the top thereof has an annular member 74 of lesser diameter than the shell 70 projecting downwardly thereinto from a point short of the upper end of the chamber 21. A top plate 75 is positioned across the upper end of the member 74 and is secured at the periphery thereof to the inner wall of the chamber 21. The top plate 75 has an outlet opening 76 in communication with a vapor outlet chamber 76 at the top of the chamber 21, the chamber 76 being separated from the chamber 21 by the top plate 75. A plurality of blades 77 extend substantially diagonally across the space 78 between the outer periphery of the member 74 and the inner periphery of the shell 70. The blades 77 are curved downwardly to impart a whirling motion to vapor flowing through the passages therebetween, as will hereinafter be fully set forth. A conical shaped member 79 is disposed adjacent the bottom of the shell 70 in spaced relationship with the outlet 73.

55 The chamber 76 is in communication with a vapor outlet ring 80 through a plurality of tubes 81. The ring 80 is in communication with a vapor outlet pipe 82 which outlet pipe communicates with the superheater header 55.

60 As shown in Fig. 5, air under pressure and of a high density is supplied to the vapor generator through conduit 83 which is in communication at one end with the vapor generator through the connection 84 and at the opposite end is connected to an air compressor 85. The air compressor 85 is driven by a gas turbine 86 which turbine is actuated, as shown, by gases of combustion from the vapor generator. The gases of combustion flow from the vapor generator through the gas outlet 68 into the conduit 81 thence to the turbine 86. Exhaust gas from the turbine flows through the conduit 88 through an economizer 89 to a stack 90. In starting up the vapor generator of the present invention, it may be necessary, in order to secure air of the proper

density and pressure, to drive the compressor 86 by a turbine or electric motor 81.

In operation, the vapor generator of the present invention is started by lighting the burner 64 which causes a stream of gases of combustion to flow downwardly in the chamber 52 and outwardly of said chamber through the gas outlet 65 thence upwardly over the vapor generating tubes 25 in the pass 30 of the passage 26. Air at the proper density and pressure is provided by the compressor 85 which is driven during the starting-up period by the turbine or motor 81, said air entering the vapor generator through the conduit 83 and connection 84. The gases flow from the pass 30 over the top of the baffles 32 and 33, downwardly over the vapor generating tubes 25 in the pass 31 and outwardly of the pass 31 through the outlet passage 66 thence outwardly of the setting through the passage gas outlet 68 to the gas turbine 86 through the conduit 87. Normally, the water level in the drum 20 extends to the line WL in the chamber 21. The circulation of water is downwardly through the downcomer 23 into the chamber 22 thence upwardly into the tubes 25 and upwardly into the water wall tubes 54 and tubes 38 through the tubes 42 and header 39. Vapor generated in the tubes 54 and 38 flows into the upper header 37 thence through the tubes 41 into the chamber 21 of the drum 20 while vapor generated in the tubes 25 flows upwardly into the chamber 21. Vapor from the chamber 21 flows therefrom through the passages between blades 71. The blades 71 impart a circular movement to the vapor as it enters the shell 70. Circular movement within the shell 70 separates liquid from vapor by centrifugal force, the liquid flowing downwardly through the bottom section 72 of the shell and into the downcomer 23 while the separated vapor flows upwardly through the outlet opening in the top 75 into the chamber 76 thence through the pipes 81 into the ring 80 whence it flows into the outlet pipe 82 thence into the superheater inlet header 55. Vapor passes into the uppermost chamber 92 in header 55 through the pass 96 into the uppermost compartment 94 in the header 56 thence serially through the next lower succeeding passes to the superheater vapor outlet 56'. In flowing through the various passes of the tubes 57, the vapor passes from a chamber 92 in header 55 through the convection section comprising the portions 58 and 59 and thence into the radiant section comprising the portion 60 then into the second convection section comprising the sections 61 and 62 of the tubes 57. From the second convection section, vapor flows into a compartment 94 of the superheater header 56. When sufficient saturated steam is flowing into superheater tubes 57, the burner 63 is lighted which causes gases of combustion to flow downwardly therefrom into the superheater furnace chamber 53. Gases of combustion flow from the superheater chamber 53 in radiant heat exchange relationship with the section 60 of the superheater tubes 57 thence in convection heat exchange relationship with the portions 58, 59, 61 and 62 of the tubes 57, thereafter passing through the screens 45 and 46 into the vapor generating furnace chamber 52 wherein the gases mix with the gases of combustion flowing downwardly from the burner 64. The mixed gases flow outwardly of the chamber 52 through the furnace gas outlet passage 65.

With this arrangement, it will be perceived that

a compact vapor generator is provided. A compact vapor generating and superheating unit is also provided in which the vapor temperature is controlled by differential firing of the vapor generating furnace 52 and the vapor superheating furnace 53 and in which saturated vapor only may be obtained by firing the vapor generating furnace only. Since the vapor generator is operated under pressure, the size of the combustion chamber and the amount of heating surface required for a given capacity of vapor generation is reduced because the density of the air and combustion gases is increased. Due to the arrangement of the parts of the vapor generator of the present invention, the speed of travel of the gases therethrough is several times as great as in the usual pressure boiler so that a very high transfer rate and corresponding reduction in the required heating surface is obtained.

Although a preferred form of the invention has been disclosed, the principles of the invention may be embodied in other forms. For example, instead of the drum 20, an upper drum and a lower drum connected by a plurality of downcomer tubes, instead of the downcomer section 23, may be used. Each of the furnaces 52 and 53 may be fired by one or more burners if desired.

Changes may be made in the form, location and arrangement of the several elements of the generator disclosed without departing from the principles of the invention. Accordingly, the invention is not to be limited excepting by the scope of the appended claims.

What is claimed is:

1. A vapor generator comprising a setting, an upper vapor and liquid container, a lower liquid container below the upper container, a bank of vapor generating tubes extending between the containers, downcomer means disposed within the bank of tubes, heat insulating means separating the downcomer from said tube bank, a furnace surrounding the bank of tubes, a superheater and also vapor generating tubes in one portion of the furnace, vapor generating tubes in another portion of the furnace, separate burners for firing each of said furnace portions, and partition means forming a passage around the tube bank and separating said bank from the furnace, the furnace having a gas outlet opening in communication with the passage and positioned to receive gases of combustion from said one furnace portion after the gases have passed in heat exchange relationship with the superheater and the vapor generating tubes and to receive the gases from said other furnace portion after the gases have passed in heat exchange relationship with the vapor generating tubes, the passage having a gas outlet through which gases flow from the passage, the furnace outlet opening and the gas outlet being so disposed in relationship to each other that gases of combustion from the furnace flow in heat exchange relationship with the tube bank in flowing through said passage from said outlet opening to the outlet.

2. A vapor generator comprising a setting, an upper vapor and liquid container, a lower liquid container substantially vertically below the upper container, a bank of substantially vertically extending vapor generating tubes between the containers, downcomer means disposed within the bank of tubes, heat insulating means separating the downcomer from the tube bank, a substantially annular shaped furnace surrounding

the bank of tubes, a superheater in one portion of the furnace, a burner for firing said one portion, a separate burner for firing another portion of the furnace, and partition means forming a passage around the tube bank and separating said bank from the furnace, the furnace having a gas outlet opening in communication with the said passage and positioned to receive gases of combustion from said one furnace portion after the gases have passed in heat exchange relationship with the superheater and to receive gases from said other portion of the furnace, the said passage having a gas outlet through which gases flow from the said passage, the furnace gas outlet opening and the said passage gas outlet being so disposed in relationship to each other and the tube bank that gases of combustion from the furnace flow into said passage through said gas outlet opening and flow in heat exchange relationship with the tube bank in flowing through said passage from said outlet opening to said outlet.

3. A vapor generator comprising a setting, a substantially annular furnace in the setting, burners spaced from each other circumferentially of the furnace, a substantially vertically extending vapor and liquid drum disposed centrally of the furnace, said drum having an upper vapor and liquid chamber, a lower liquid chamber and an elongated connecting chamber extending along the vertical axis of the drum, the connecting chamber being of lesser diameter than the upper and lower chambers, a bank of vapor generating tubes adjacent the connecting chamber and connecting said upper and lower chambers, the width of the tube bank at the point of connection with said chambers being less than the diameter of the chambers, heat insulating means separating the connecting chamber from the tube bank, partition means forming a passage around the tube bank and separating the bank from the furnace, the furnace having a gas outlet opening in communication therewith and with said passage and through which gases of combustion produced by said burners flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, and a superheater disposed in heat exchange relationship with the gases flowing from at least one but not all of the burners to the gas outlet.

4. Vapor generating apparatus comprising a vapor generator having a setting, a substantially annular furnace in the setting, burners spaced from each other circumferentially of the furnace, means for introducing air under pressure to the furnace, a substantially vertically extending vapor and liquid drum disposed centrally of the furnace, said drum having an upper vapor and liquid chamber, a lower liquid chamber and an elongated connecting chamber extending along the vertical axis of the drum, the connecting chamber being of lesser diameter than the upper and lower chambers, a bank of vapor generating tubes adjacent the connecting chamber and connecting said upper and lower chambers, the width of the tube bank at the point of connection with said chambers being less than the diameter of the chambers, heat insulating means separating the connecting chamber from the tube

bank, partition means forming a passage around the tube bank and separating the bank from the furnace, the furnace having a gas outlet opening in communication therewith and with said passage and through which gases of combustion produced by said burners flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, and a superheater disposed in heat exchange relationship with the gases flowing from at least one but not all of the burners to the gas outlet.

5. A vapor generator comprising a setting, a substantially annular furnace in the setting, a substantially vertically extending vapor and liquid drum disposed centrally of the furnace, said drum having an upper vapor and liquid chamber, a lower liquid chamber and an elongated connecting chamber extending along the vertical axis of the drum, the connecting chamber being of lesser diameter than the upper and lower chambers, a bank of vapor generating tubes adjacent the connecting chamber and connecting said upper and lower chambers, the width of the tube bank at the point of connection with said chambers being less than the diameter of the chambers, heat insulating means separating the connecting chamber from the tube bank, rows of spaced tubes extending transversely of the furnace and dividing it into a vapor generating furnace chamber and a superheater furnace chamber, burner means for firing the vapor generating furnace chamber, burner means for firing the superheater furnace chamber, and partition means forming a passage around the tube bank and separating the bank from the furnace, the furnace having a gas outlet opening in communication with the vapor generating furnace chamber and said passage and through which outlet gases of combustion from both of said burner means flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, and a superheater disposed in said superheater furnace chamber.

6. A vapor generator comprising a setting, a substantially annular furnace in the setting, a substantially vertically extending vapor and liquid drum disposed centrally of the furnace, said drum having an upper vapor and liquid chamber, a lower liquid chamber and an elongated connecting chamber extending along the vertical axis of the drum, the connecting chamber being of lesser diameter than the upper and lower chambers, a bank of vapor generating tubes adjacent the connecting chamber and connecting said upper and lower chambers, the width of the tube bank at the point of connection with said chambers being less than the diameter of the chambers, heat insulating means separating the connecting chamber from the tube bank, rows of spaced tubes extending transversely of the furnace and dividing it into a vapor generating furnace chamber and a superheater furnace chamber, burner means for firing the vapor generat-

11

tion means forming a passage around the tube bank and separating said bank from the furnace, the passage having a gas inlet opening adjacent one end thereof in communication therewith and with the furnace and a gas outlet opening through which gases flow from the passage, the inlet and outlet openings being so disposed in relationship to each other that gases of combustion from the furnace flow in heat exchange relationship with the tube bank in flowing through said passage from the inlet to the outlet thereof, and centrifugal vapor and liquid separating means in the upper vapor and liquid chamber comprising a cylindrical member having an opening in the upper part in communication with said chamber and the interior of the cylindrical member, means forming curved passages in said opening for imparting a whirling movement to the vapor and liquid, the cylindrical member having a liquid outlet at the bottom thereof in communication with said connecting chamber and a vapor outlet in communication with the means communicating with the annular offtake pipe.

10. A vapor generator comprising a setting, an upper vapor and liquid container, a lower liquid container below the upper container, a bank of vapor generating tubes extending between the containers, downcomer means disposed within the bank of tubes, a furnace surrounding the bank of tubes, a superheater in one portion of the furnace, vapor generating tubes in another portion of the furnace, separate burners for firing each of said furnace portions, and partition means forming a passage around the tube bank and separating said bank from the furnace, the furnace having a gas outlet opening in communication with the said passage and positioned to receive gases of combustion from said one furnace portion after the gases have passed in heat exchange relationship with the superheater and to receive the gases from said other furnace portion after the gases have passed in heat exchange relationship with the vapor generating tubes, the said passage having a gas outlet through which gases flow from the said passage, the said passage furnace gas outlet opening and the gas outlet being so disposed in relationship to each other and the tube bank that gases of combustion from the furnace flow into said passage through said gas outlet opening and flow in heat exchange relationship with the tube bank in flowing through said passage from said outlet opening to said outlet.

11. A vapor generator comprising a setting, an upper vapor and liquid container, a lower liquid container below the upper container, a bank of vapor generating tubes extending between the containers, downcomer means disposed within the bank of tubes, a cylindrically shaped furnace surrounding the bank of tubes, a superheater in one portion of the furnace, vapor generating tubes in another portion of the furnace, said furnace portions being in communication with each other, separate burners for firing each of said furnace portions, and partition means forming a passage around the tube bank and separating said bank from the furnace, the furnace having a gas outlet opening in communication with the said passage and positioned to receive gases of combustion from both furnace portions after the gases from said one portion have passed in heat exchange relationship with the superheater and after the gases from both of said furnace portions have passed in heat exchange relationship with the vapor generating tubes, the said passage

70

75

12

having a gas outlet through which gases flow from the passage, the furnace gas outlet opening and the said passage gas outlet being so disposed in relationship to each other and the tube bank that gases of combustion from the furnace flow into said passage through said gas outlet opening and flow in heat exchange relationship with the tube bank in flowing through said passage from said outlet opening to said outlet.

12. A vapor generator comprising a setting, a substantially annular furnace in the setting, burners spaced from each other circumferentially of the furnace, a substantially vertically extending vapor and liquid drum disposed centrally of the furnace, said drum having an upper vapor and liquid chamber, a lower liquid chamber and an elongated connecting chamber extending substantially vertically between said chambers, the connecting chamber being of lesser diameter than the upper and lower chambers, a bank of vapor generating tubes adjacent the connecting chamber and connecting said upper and lower chambers, partition means forming a passage around the tube bank and separating the bank from the furnace, the furnace having a gas outlet opening in communication therewith and with the passage and through which gases of combustion produced by said burners flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, and a superheater disposed in heat exchange relationship with the gases flowing from at least one but not all of the burners to the gas outlet opening.

13. A vapor generator comprising a setting, an upper vapor and liquid container, a lower liquid container below the upper container, a bank of vapor generating tubes extending between the containers, downcomer means disposed within the bank of tubes, a furnace in the setting surrounding the bank of tubes, rows of spaced tubes extending transversely of the furnace and dividing it into a vapor generating furnace chamber and a superheating furnace chamber, a superheater in the superheating furnace chamber, vapor generator tubes in the vapor generating furnace, burners means for firing the vapor generating furnace chamber, burner means for firing the superheating furnace chamber, and partition means forming a passage around the tube bank and separating the bank from the furnace, the furnace having a gas outlet opening in communication with the vapor generating furnace chamber and the passage and through which outlet gases of combustion from both of said burner means flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said furnace gas passage from said outlet opening to the passage gas outlet opening.

14. A vapor generator comprising a setting, an upper vapor and liquid container, a lower liquid container below the upper container, a bank of vapor generating tubes extending between the containers, downcomer means disposed within the bank of tubes, a furnace in the setting sur-

ing furnace chamber, burner means for firing the superheater furnace chamber, partition means forming a passage around the tube bank and separating the bank from the furnace, the furnace having a gas outlet opening in communication with the vapor generating furnace chamber and with the passage and through which gases of combustion from both of said burner means flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, and a superheater in said superheater furnace chamber having a portion thereof in convection heat exchange relationship and another portion in radiant heat exchange relationship with gases of combustion from the burner means for firing said superheater furnace chamber.

7. A vapor generator comprising a setting, a substantially annular furnace in the setting, a substantially vertically extending vapor and liquid drum disposed centrally of the furnace, said drum having an upper vapor and liquid chamber, a lower liquid chamber and an elongated connecting chamber extending along the vertical axis of the drum, the connecting chamber being of lesser diameter than the upper and lower chambers, a bank of vapor generating tubes adjacent the connecting chamber and connecting said upper and lower chambers, the width of the tube bank at the point of connection with said chambers being less than the diameter of the chambers, heat insulating means separating the connecting chamber from the tube bank, rows of spaced tubes extending transversely of the furnace and dividing it into a vapor generating furnace chamber and a superheater furnace chamber, burner means for firing the vapor generating furnace chamber and a superheater furnace chamber, burner means for firing the superheater furnace chamber, partition means forming a passage around the tube bank and separating the bank from the furnace, the furnace having a gas outlet opening through said partition in the vapor generating furnace chamber through which gases of combustion from both of said burner means flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, a substantially vertically extending superheater inlet header outside of and adjacent to the superheater furnace chamber, means connecting said inlet header to the upper vapor and liquid chamber of the drum, a substantially vertically extending superheater outlet header outside of and adjacent to the superheater furnace chamber, said inlet header and said outlet header being spaced from one another circumferentially of the superheater furnace chamber, and a plurality of substantially horizontally extending superheater tubes connecting said headers, the tubes having end portions that extend from the headers transversely of the superheater chamber thence toward the headers to the inner peripheral wall of the furnace and a portion intermediate the end por-

tions extending along said peripheral wall of the furnace.

8. A vapor generator comprising a setting, a substantially annular furnace in the setting, a substantially vertically extending vapor and liquid drum disposed centrally of the furnace, said drum having an upper vapor and liquid chamber, a lower liquid chamber and an elongated connecting chamber extending along the vertical axis of the drum, the connecting chamber being of lesser diameter than the upper and lower chambers, a bank of vapor generating tubes adjacent the connecting chamber and connecting said upper and lower chambers, the width of the tube bank at the point of connection with said chambers being less than the diameter of the chambers, heat insulating means separating the connecting chamber from the tube bank, rows of spaced tubes extending transversely of the furnace and dividing it into a vapor generating furnace chamber and a superheater furnace chamber, burner means for firing the vapor generating furnace chamber, burner means for firing the superheater furnace chamber, partition means forming a passage around the tube bank and separating the bank from the furnace, the furnace having a furnace gas outlet opening in communication with the vapor generating furnace chamber and the passage and through which gases of combustion from both of said burner means flow into said passage, the passage having a passage gas outlet through which gases flow therefrom and from the setting, the outlet and the outlet opening being so disposed in relationship to each other that gases of combustion from the furnace flow in heat exchange relationship with the tube bank in flowing through said passage from said outlet opening to the outlet, an annular upper header adjacent the top of the peripheral wall of the furnace, tubular means connecting the annular upper header and the upper vapor and liquid chamber, an annular lower header adjacent the bottom of the peripheral wall of the furnace, tubular members connecting the annular lower header and the lower liquid chamber of the drum, tubes extending between said upper and lower headers along the peripheral wall of the vapor generating surface, other tubes connected at their opposite ends to said upper and lower annular headers, said other tubes having end portions which extend respectively transversely and radially of the roof and floor of the annular furnace and an intermediate portion extending substantially vertically along said partition means, and a superheater disposed in the superheater furnace chamber.

9. A vapor generator comprising a setting, a furnace in the setting, means for firing the furnace, a substantially vertically extending vapor and liquid drum in the setting having an upper vapor and liquid chamber, a lower liquid chamber and an elongated connecting chamber along the vertical axis of the drum, the connecting chamber being of lesser diameter than the upper and lower chambers, an annular vapor offtake pipe adjacent the upper end of the drum, means communicating with said pipe and the upper chamber through which vapor passes from the drum into the offtake pipe, a bank of vapor generating tubes adjacent the connecting chamber and connecting said upper and lower chambers, the width of the tube bank at the point of connection with said chambers being less than the diameter of the chambers, heat insulating means separating the connecting chamber from the tube bank, parti-

rounding the bank of tubes, a superheater in one portion of the furnace, said superheater having a part thereof in radiant heat exchange relationship and another part in convection heat exchange relationship with gases of combustion in said one portion, vapor generating tubes in another portion of the furnace, separate burners for firing each of said furnace portions, and partition means forming a passage around the tube bank and separating said bank from the furnace, the furnace having a gas outlet opening in communication with the passage and positioned to receive gases of combustion from said one furnace portion after the gases have passed in heat exchange relationship with the superheater and to receive the gases from said other furnace portion after the gases have passed in heat exchange relationship with the vapor generating tubes, the passage having a gas outlet through which gases flow from the passage, the furnace outlet opening and the gas outlet being so disposed in relationship to each other that gases of combustion from the furnace flow in heat exchange relationship with the tube bank in flowing through said passage from said outlet opening to the outlet.

15. A vapor generator comprising a setting, a substantially annular furnace in the setting having a vapor generating chamber and a superheater chamber therein, said chambers being in communication with one another, an upper vapor and liquid container, a lower liquid container below and in substantial vertical alignment with the upper container, a bank of vapor generating tubes extending between the containers, downcomer means disposed within the bank of tubes, burner means for firing the vapor generating furnace, burner means for firing the superheater furnace chamber, partition means forming a passage around the tube bank and separating the bank from the furnace, the furnace having a gas outlet opening in communication with the vapor generating furnace chamber and the passage and through which gases of combustion from both of said burner means flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, and a superheater in said superheater furnace chamber comprising tubular members having a portion thereof extending circumferentially along the wall of said chamber and in radiant heat exchange relationship with gases of combustion and another portion extending into the path of and in convection heat exchange relationship with gases flowing from the superheater chamber to the vapor generating furnace.

16. A vapor generator comprising a setting, a substantially annular furnace in the setting having a vapor generating chamber and a superheater chamber therein, said chambers being in communication with one another, an upper vapor and liquid container, a lower liquid container below and in substantial vertical alignment with the upper container, a bank of vapor generating tubes extending between the containers, downcomer means disposed within the bank of tubes, burner means for firing the vapor generating furnace chamber, burner means for firing the superheater furnace chamber, partition means forming a passage around the tube bank and sepa-

rating the bank from the furnace, the furnace having a gas outlet opening through said partition in the vapor generating furnace chamber through which gases of combustion from both of said burner means flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, a substantially vertically extending superheater inlet header outside of and adjacent to the superheater furnace chamber, means connecting said inlet header to the upper vapor and liquid chamber of the drum, a substantially vertically extending superheater outlet header outside of and adjacent to the superheater furnace chamber, said inlet header and said outlet header being spaced from one another circumferentially of the superheater furnace chamber, and a plurality of substantially horizontally extending superheater tubes connecting said headers, the tubes having end portions that extend from the headers transversely of the superheater chamber thence toward the headers to the inner peripheral wall of the furnace and a portion intermediate the end portions extending along said peripheral wall of the furnace.

17. A vapor generator comprising a setting, a substantially annular furnace in the setting having a vapor generating chamber and a superheater chamber therein, said chambers being in communication with one another, an upper vapor and liquid container, a lower liquid container below and in substantial vertical alignment with the upper container, a bank of vapor generating tubes extending between the containers, downcomer means disposed within the bank of tubes, burner means for firing the vapor generating furnace chamber, burner means for firing the superheater furnace chamber, partition means forming a passage around the tube bank and separating the bank from the furnace, the furnace having a gas outlet opening through said partition in the vapor generating furnace chamber through which gases of combustion from both of said burner means flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, an annular upper header adjacent the top of the peripheral wall of the furnace, tubular means connecting the annular upper header and the upper vapor and liquid chamber, an annular lower header adjacent the bottom of the peripheral wall of the furnace, tubular members connecting the annular lower header and the lower liquid chamber of the drum, tubes extending between said upper and lower headers along the peripheral wall of the vapor generating surface, other tubes connected at their opposite ends to said upper and lower annular headers, said other tubes having end portions which extend respectively transversely and radially of the roof and floor of the annular furnace and an intermediate portion extending substantially vertically along said partition means, and a superheater disposed in the superheater furnace chamber.

18. A vapor generator comprising a setting having a substantially annular furnace chamber therein, an upper vapor and liquid container, a lower liquid container below and in substantial vertical alignment with the upper container, a bank of vapor generating tubes extending between the containers, downcomer means disposed within the bank of tubes, burners spaced from each other circumferentially of the furnace, partition means forming a passage around the tube bank and separating the bank from the furnace, the furnace having a gas outlet opening through said partition so positioned that gases of combustion from both of said burner means flow into said passage, the passage having a gas outlet through which gases flow therefrom and from the setting, the outlet and the outlet opening being so disposed in relationship to each other that gases of combustion from the furnace flow in heat exchange relationship with the tube bank in flowing through said passage from said furnace gas outlet opening to the passage gas outlet, an annular upper header adjacent the top of the peripheral wall of the furnace, tubular means connecting the annular upper header and the upper vapor and liquid chamber, an annular lower header adjacent the bottom of the peripheral wall of the furnace, tubular members connecting the annular lower header and the lower liquid chamber of the drum, tubes extending between said upper and lower headers along the peripheral wall of the vapor generating surface, and other tubes connected at their opposite ends to said upper and lower annular headers, said other tubes having end portions which extend respectively transversely and radially of the roof and floor of the annular furnace and an intermediate portion extending substantially vertically along said partition means.

19. A vapor generator comprising a setting, a furnace in the setting, means for firing the furnace, an upper vapor and liquid container, a lower liquid container below and in substantial vertical alignment with the upper container, a bank of vapor generating tubes extending between the containers, downcomer means disposed within the bank of tubes, an annular off-take pipe adjacent the upper end of said upper container, means communicating with said pipe and the upper chamber through which vapor passes from said upper container into the off-take pipe, partition means forming a passage around the tube bank and separating said bank from the furnace, the passage having a gas inlet opening adjacent one end thereof in communication therewith and with the furnace and a gas outlet opening through which gases flow from the passage, the inlet and outlet openings

being so disposed in relationship to each other that gases of combustion from the furnace flow in heat exchange relationship with the tube bank in flowing through said passage from the inlet to the outlet thereof, and centrifugal vapor and liquid separating means in the upper vapor and liquid chamber comprising a cylindrical member having an opening in the upper part in communication with said chamber and the interior of the cylindrical member, means forming curved passages in said opening for imparting a whirling movement to the vapor and liquid, the cylindrical member having a liquid outlet at the bottom thereof in communication with said connecting chamber and a vapor outlet in communication with the means communicating with the annular offtake pipe.

20. A vapor generator comprising a setting, an upper vapor and liquid container, a lower liquid container below the upper container, a bank of vapor generating tubes extending between the containers, downcomer means disposed within the bank of tubes, a furnace surrounding the bank of tubes, means for supplying air under pressure to the furnace, a superheater in one portion of the furnace, vapor generating tubes in another portion of the furnace, separate burners for firing each of said furnace portions, and partition means forming a passage around the tube bank and separating said bank from the furnace, the furnace having a gas outlet opening in communication with the passage and position to receive gases of combustion from said one furnace portion after the gases have passed in heat exchange relationship with the superheater and to receive the gases from said other furnace portion after the gases have passed in heat exchange relationship with the vapor generating tubes, the passage having a gas outlet through which gases flow from the passage, the furnace outlet opening and the gas outlet being so disposed in relationship to each other that gases of combustion from the furnace flow in heat exchange relationship with the tube bank in flowing through said passage from said outlet opening to the outlet.
